UNITED STATES PATENT OFFICE.

GEORGE A. RUTHERFORD, OF NEW YORK, N. Y.

SUPPORT FOR OPERATORS' INSTRUMENTS.

SPECIFICATION forming part of Letters Patent No. 665,470, dated January 8, 1901.

Application filed December 24, 1897. Serial No. 663,358. (No model.)

To all whom it may concern:

Be it known that I, GEORGE A. RUTHERFORD, of New York city, in the county and State of New York, have invented a new and 5 Improved Support for Operator's Instruments, of which the following is a full, clear, and exact description.

The object of the invention is to provide a new and improved support more especially 10 designed for use on the head of an operator on telegraphic instruments, such as telegraph-sounders, telephone-receivers, and other instruments requiring a head-support, the device being constructed for convenient adjustment 15 to bring the instrument in proper relation to the ear of the operator and without undue strain on the operator's head.

The invention consists of novel features 20 and parts and combinations of the same, as will be fully described hereinafter, and pointed out in the claims.

Reference is to be had to the accompanying 25 drawings, forming a part of this specification, in which similar characters of reference indicate corresponding parts in both figures.

Figure 1 is a perspective view of the improvement as applied, and Fig. 2 is an enlarged perspective view of the improvement.

The instrument A to be supported in close 30 proximity to one of the operator's ears is rigidly connected by a bracket B with one end C' of a band C made of hard rubber, spring metal, or other suitable material and bent in inverted-U shape to extend in a vertical 35 plane across the top of the operator's head approximately from one ear to the other, the free end of the band C flaring outwardly, as is plainly indicated in Fig. 2. On the end C' adjacent to the attachment of the bracket B 40 is fulcrumed at D' a second band D, standing at an angle to the band C and adapted to be passed around the rear portion of the operator's head to connect at its other end D² with the free end of the other band C. The free 45 end D² of the band D is formed with an elongated slot D³, adapted to engage a clamping-screw E, carried on the free end of the band C and located directly opposite the fulcrum or pivot D', so as to permit of swinging the 50 band D into the desired angular position. When the nut of the clamping-screw E is loosened, the end D² of the band D can be ad-

justed in a longitudinal direction to lengthen or shorten the portion of the band D extending from one side of the band C to the other, 55 according to the shape of the operator's head. After the desired adjustment is made the nut of the clamping-screw E is screwed up to securely fasten the free end D² of the band D in place.

At the end D' and at the inside thereof directly above the instrument A is secured a button F, of soft rubber or other suitable material, adapted to rest against the side of the operator's head and above the ear to properly 65 hold the inner face of the instrument in proper relation to the operator's ear without unduly pressing the same or producing an undesirable strain on the head.

The end C² of the band C, which extends 70 opposite the instrument A, is flared outwardly to prevent injury to the ear of the operator when the device is applied to the head and also serves as a handle in placing and adjusting the support upon the operator's head. 75

It is understood that the band C is at all times in a fixed relation to the bracket B and the instrument A, while the other band D is adjustable on the band C, according to the shape of the operator's head, the said band 80 extending approximately in a horizontal direction—that is, at a right angle to the band C, which extends in a vertical plane.

Having thus fully described my invention, I claim as new and desire to secure by Letters 85 Patent—

1. A support of the class described, comprising a vertically-disposed flexible band adapted to engage the operator's head from ear to ear over the top of the head, one end 90 of the band being adapted to carry the instrument, a second flexible band standing at an angle to the first-named band, and adapted to engage the rear portion of the head in an approximately horizontal direction, the ends 95 of the second band having a pivotal connection with the opposite ends of the first-named band, and a button projecting from the inside of the first-named band at the instrument-supporting end, for holding the instrument in proper relation to the ear and for relieving the head of undue strain, substantially as shown and described.

2. A support of the class described, com-

prising two connected bands adapted to fit over the head of the operator, and a button projecting from the inside of one of the bands adjacent to the instrument-carrying end of the support for the purpose set forth.

3. A support of the class described, comprising two flexible bands adapted to fit over the head of the operator, one of the bands being adjustably connected with the other, and a button projecting from the inside of one of the bands adjacent to the instrument-carrying end of the support for the purpose set forth.

4. A support of the class described, comprising a flexible band made inverted-U shape with sides or arms of unequal length,

the short arm of said band being adapted to carry the instrument and the other or long arm extending opposite the supported instrument and being flared outwardly at its end, and a second flexible U-shaped band pivotally connected at its ends with the arms of the first-named band at a point opposite to each other, with the supported instrument at one side and the said outwardly-curved end of the band at the other side opposite to each other and below the point of pivotal connection between the bands.

GEORGE A. RUTHERFORD.
